UNITED STATES PATENT OFFICE.

JOHN H. BUSCHER, OF OTTAWA, OHIO.

FENCE-POST.

SPECIFICATION forming part of Letters Patent No. 359,666, dated March 22, 1887.

Application filed July 23, 1886. Serial No. 208,884. (No model.)

To all whom it may concern:

Be it known that I, JOHN H. BUSCHER, a citizen of the United States, residing at Ottawa, in the county of Putnam, State of Ohio, have 5 invented certain new and useful Improvements in Fence-Posts, of which the following is a specification, reference being had therein to the accompanying drawings.

This invention consists of a loop-formed metallic post connected with a stone or other solid block embedded in the ground and having an intervening board for the continuous fence-wires to be secured to, as hereinafter specified.

15 To more particularly describe the invention, I will refer to the accompanying drawings, in which—

Figure 1 represents a section of a continuous-wire fence, with its posts and fastenings, 20 constructed according to my invention. Fig. 2 is a side view of a post for the same.

The same letters appearing on both figures indicate like parts.

A represents a block of stone or other suitable material, which should be inserted in the ground a sufficient depth to render it firm and steady and to project a suitable height above the surface.

C is a bent iron rod of U shape at its upper 30 end, and having two parallel legs, c c, of suitable distance apart to receive the upright board a between them. The two lower ends of these legs are to be securely inserted in the block A.

For a continuous-wire fence the piece of 35 board a is inserted between the legs c c of the post, to which the wires d are secured by staples e, one on either side of the leg c, by which they are prevented from slipping down, and at the same time caused to form a loop over or 40 half around the leg c, which serves to brace the post and keep it upright.

I am aware that iron posts have been used in which staples have been inserted in slots in said posts to support the wires of the fence; 45 also, that such posts have been grooved around to receive cross or lace wires to bind the legs together and form supports for the rails of a board fence; but these, being more expensive constructions, and at the same time detracting 50 from the strength of the post, are not claimed by me.

What I claim as new, and desire to secure by Letters Patent, is—

The loop-formed metallic post c and upright 55 board a, having the continuous fence-wires bent over or half around the leg c of the iron post and secured by staples on either side to the board a, all arranged and combined as shown and described.

In testimony whereof I affix my signature in presence of two witnesses.

JOHN H. BUSCHER.
